UNITED STATES PATENT OFFICE.

FRED DAVIS, OF PONCA CITY, OKLAHOMA.

CAR-REPLACING MEANS.

Application filed March 6, 1926. Serial No. 92,933.

My present invention has to do with the replacing or rerailing of locomotive cars and the like; and it contemplates the provision of means for the purpose stated, 5 possessed of the practical advantages hereinafter explicitly ascribed to it.

The invention in all of its details will be fully understood from the following description and claims when the same are read 10 in connection with the drawings, accompanying and forming part of this specification, in which:—

Figure 1 is a plan view illustrating the preferred embodiment of my invention as 15 the same appears when its members are properly arranged relative to the rails of a railway.

Figure 2 is an inverted plan view showing one of the members of my improvement. 20 Figure 3 is a transverse section taken in the plane indicated by the line 3—3 of Figure 1, and illustrating the manner in which the said member is engaged with spike heads and held against lateral movement away 25 from the adjacent rail.

Figure 4 is a side elevation of the said member.

Figure 5 is a side elevation of the other member comprised in the improvement.

30 Figure 6 is an inverted plan view of the latter member.

Figure 7 is a transverse section taken in the plane indicated by the line 7—7 of Figure 1.

35 Similar numerals of reference designate corresponding parts in all of the views of the drawings.

I show in Figure 1, the rails 1 and 2 of a railway, and also show in Figures 1 and 40 2, and 3 as well as in Figure 4 the member 3 of my improvement. The said member 3 is preferably formed in appropriate manner in one sheet, and it will be noted that it has a straight side 4 and a dished side 5. 45 It will also be noticed that the member has a top 6, a longitudinal flange 7 pendent from the top 6, a longitudinal dished flange 8 also pendent from the top 6, and transverse pendent flanges 9 spaced apart and interposed between the flanges 7 and 8. The top 6 includes an intermediate portion 10 slightly inclined in the direction of the width of the member 3, and inclined planes 11 which extend longitudinally in opposite 50 directions from the intermediate portion 10. 55 On the top 6 the member 3 is provided with

a rib 12 which describes an obtuse angle and is inclined from the vertical and is spaced from the dished edge 5 of the member and is braced at the points 13, Figure 1. In the practical use of the member 3, the pendent flange 7 is designed to be engaged with the heads of adjacent spikes 14, Figure 3, the inner edge portion of the member 3 at that time being interposed between the underside of the ball or head of the rail 60 and the base thereof as clearly brought out in said Figure 3. By virtue of this arrangement it will be manifest that casual lateral movement of the member 3 away from the rail 2 is precluded, and hence the efficiency of the member 3 is enhanced. In 65 this connection it will be understood from Figures 2 and 4, that the member 3 is provided adjacent to its ends with pendent toes 15. There are preferably three toes 15 at 70 each end of the member 3, and they serve when the member 3 is in use to engage adjacent sleepers or cross ties 16 and in that way effectively prevent casual endwise movement of the member 3 when said 75 member is in use, and hence also contribute to the efficiency of the member 3. Manifestly it is within the purview of my invention to form the member 3 characterized as described of any material or materials 80 consonant with the purpose to which the said member 3 is put.

The other member of my improvement is designated by 30 and includes a body portion and a laterally swingable tongue 31. 85 The said body portion of the member 30 includes an inclined plane 32 which is gradually increased in width from an intermediate portion of the body to one end thereof and is provided with shallow side flanges 33. At its inner end the inclined plane 32 of the member 30 is merged into a platform portion 34, and on the said platform portion 34 are spaced longitudinal ribs 35 which are diminished in width from their heel ends to points, Figure 1, and have their heel ends rounded as designated by 36 and best shown in Figure 5. Arranged on the platform 34 and fixed with respect thereto is a bar portion 37 which extends beyond the end of the platform 34 remote from the inclined plane 32. The laterally swingable tongue 31 is pivotally connected at 38 to the said bar portion 37.

For the sake of convenience I will hereinafter refer to the member 3 as the female

member of my improvement and to the member 30 as the male member of said improvement. In this connection it will be understood that the rib 12 of the member 5 3 has for its function to cause a car or locomotive to slip laterally toward the rail 2, this being advantageous in the rerailing of a car or locomotive. It will also be noticed that the member 30 of my improvement is 10 designed to rest over the rail 1, and the tongue 31 has for its function to guide a car or locomotive to the rail 1 if the car or locomotive in such a position that placing 15 of the male member 30 over the rail is prevented.

By comparison of Figures 1 and 7, the working position of the member 30 relative to the rail 1 will be readily appreciated.

It will be apparent from the foregoing 20 that my improvement is susceptible of being expeditiously and easily handled, and when the members are properly placed relative to the rails 1 and 2, the improvement will serve efficiently in performing the function ascribed to it.

I have specifically described the construction and relative arrangement of the parts embraced in the present and preferred embodiment of my invention in order to impart 25 a full, clear and exact understanding of the same. I do not desire, however, to be understood as limiting myself to the precise construction and arrangement as disclosed, my invention being defined by my 30 appended claims within the scope of which changes in structure and in arrangement may be made without departure from my invention.

Having described my invention, what I 40 claim and desire to secure by Letters Patent, is:—

1. Car replacing means comprising two members; one of the said members being 45 designed to be arranged at the inner side of a rail and having a pendent longitudinal flange to engage spike heads and also having end toes to prevent endwise shifting, and the said member also having inclined planes at its upper side and a rib at said side describing an obtuse angle, and the other member being adapted to be placed over an 50 opposite rail and having an inclined plane gradually increased in width outwardly and a platform portion and spaced ribs on said platform portion and further having a fixed bar extending from the end of the platform portion remote from the inclined plane, and a laterally swingable tongue shaped to conform to the platform portion and the inclined plane and pivoted at its heel end to the said bar portion.

2. Car replacing means comprising two members; one of the said members being 60 designed to be arranged at the inner side of a rail and having a pendent longitudinal

flange to engage spike heads and also having end toes to prevent endwise shifting, and the said member also having inclined planes at its upper side and a rib at said side describing an obtuse angle, and the other member being adapted to be placed over an opposite rail and having an inclined plane gradually increased in width outwardly and a platform portion and spaced ribs on said platform portion and further having a fixed bar extending from the end of the platform portion remote from the inclined plane, and a laterally swingable tongue shaped to conform to the platform portion and the inclined plane and pivoted at its heel end to the said bar portion; said member also having longitudinal spaced pendent flanges for the adequate support of the inclined plane and the platform portion.

3. Car replacing means comprising two members; one of the said members being designed to be arranged at the inner side of a rail and having a pendent longitudinal flange to engage spike heads and also having end toes to prevent endwise shifting, and the said member also having inclined planes at its upper side and a rib at said side describing an obtuse angle, and the other member being adapted to be placed over an opposite rail and having an inclined plane gradually increased in width outwardly and a platform portion and spaced ribs on said platform portion and further having a fixed bar extending from the end of the platform portion remote from the inclined plane, and a laterally swingable tongue shaped to conform to the platform portion and the inclined plane and pivoted at its heel end to the said bar portion; said ribs on the platform portion being increased in width toward their heel ends and having said ends rounded, and the member being also provided with longitudinal spaced flanges for the support of the inclined plane and the platform portion.

4. A car replacing member having an inclined plane and a portion of platform type at the upper end of said plane and also having supporting means and a bar extending longitudinally of and beyond the end of the platform portion remote from the inclined plane, and equipped with a laterally swingable tongue, extending from the heel of said bar and shaped in conformity to and resting adjacent to the inclined plane and the platform and pivoted to the inner end of the said bar portion.

5. A car replacing member having an inclined plane and a portion of platform type at the upper end of said plane and also having supporting means and a bar extending from the end of the platform portion remote from the inclined plane, and equipped with a laterally swingable tongue shaped in conformity to and resting adjacent to the in-

clined plane and the platform and pivoted to the inner end of the said bar portion; the said inclined plane of the member being tapered or gradually reduced in width inwardly and being provided with side flanges, and the said platform portion being of increased width at the point where it joins the inclined plane and being provided with ribs of taper form and having rounded inner edges or ends.

6. A car replacing member comprising a body having a platform and an inclined plane and also having a bar portion fixed to and extending from the end of the platform portion remote from the inclined plane, and a laterally swingable tongue shaped to con-

form to the platform and the inclined plane and pivotally connected with the said bar portion.

7. A car replacing member comprising a body with a platform portion and an inclined plane and with spaced ribs on said platform, a bar portion fixedly connected to the platform portion and extending from the end thereof remote from the inclined plane, and a pivoted and laterally swingable tongue shaped in conformity to and movable on the platform and the inclined plane.

In testimony whereof I affix my signature.

FRED DAVIS.
